CLAMP FOR CAN BODY FORMING MACHINE
Wayne F. Wolfe, Orange, Calif., assignor to United Can Company, Fullerton, Calif., a corporation of Delaware

Filed Nov. 3, 1966, Ser. No. 591,762

7 Claims. (Cl. 113—8)

This invention relates to machines for forming can bodies from flat blanks, and, more particularly, to apparatus for alternately clamping and releasing a can blank against a mandrel on which the can body is formed.

Generally in machines for forming metal can bodies, a series of flat metal blanks are fed past a station at which the two side edges of each blank are folded to form elongate hooks. Then at a subsequent station, the blanks are formed around a cylindrical mandrel by a pair of forming wings which open and close about the mandrel much like a pair of pliers to inter-engage the hooked edges so that the blanks retain their cylindrical shape. The mandrel then is expanded to tightly engage the hooks and the seam is pounded from below by a bumper mechanism to firmly clench the edges. The mandrel usually is cantilevered so that the cylindrical can body can then be conveyed off the free end of the mandrel to receive can ends at another station.

In order to prevent misalignment of the blank and to provide an anvil to reinforce the mandrel against the bumping force, it is essential that the blank be clamped against the mandrel from above while the wings form the cylindrical body and the blank is expanded and bumped. This can be done by an elongate clamping shoe which is disposed over the mandrel and reciprocates from a clamping position to a release position. However, in machines producing four hundred can bodies per minute and more, the clamp must engage and release the blank at a tremendous rate. Moreover, it must exert sufficient force to securely hold a can blank in place while it is being shaped into a body, yet because the cantilevered mandrel is subject to bending, it is critical that the clamp not apply excessive pressure. Thus, uniformity of clamping pressure is essential. The prior art devices have encountered considerable problems in accomplishing these objects in the extremely fast operation required for an economical can forming machine.

One prior art approach employs sliding wedges to actuate the clamping shoe. One wedge remains fixed during normal operation. The other is forced between the fixed wedge and the shoe to apply pressure to the shoe, and then is forced out from the wedging position to release the pressure after the blank has been formed. However, application of sufficient force to operate the movable wedge can cause difficulty in high speed operation. Releasing the pressure can be a particular problem as the wedges sometimes "freeze" together. Moreover, the desired goal of uniformity of pressure is difficult to achieve.

A refinement of that prior art apparatus instead actuates the clamping shoe by forcing a wiper cam against an inclined surface formed on the top of the upper wedge. However, dirt and other foreign matter can accumulate on both the inclined surface and the wiper cam causing variances in the amount of pressure applied by the shoe. Moreover, the impact of the wiper cam on the inclined surface imparts considerable shock to the machine when operating at high speeds, and tends to wear and gall both parts. Irregularities developed from the impact can vary the clamping pressure and even cause the wiping cam to lock against the inclined surface in the clamped position.

This invention is directed to an improved can forming machine structure which eliminates the use of sliding wedges or impacting cam surfaces to actuate the clamp, and substitutes well lubricated rotary bearing surfaces which are less subject to wear, and are less likely to be

2

affected by surface irregularities. The advantage of the rotary bearing surfaces are compounded at high speeds such as those at which modern can forming machines operate.

5 The rotary bearing surfaces are provided in a can forming machine constructed in accordance with this invention by opposed concave arcuate bearing surfaces in a portion of the clamping shoe assembly and an elongate shaft which is rotatably mounted alongside it. Two spaced-apart tongue portions of a link are inserted in the concavities to connect the clamping shoe assembly and shaft. Each of the tongue portions has an arcuate bearing surface conforming to the mating concave bearing surface. As the shaft is oscillated, the link forces the clamping shoe to the clamping position and then removes the pressure so that the can body can be conveyed on.

A further feature of this invention resides in the use of an overload device in the connecting rod which oscillates the elongate shaft. If two can bodies rather than one are inadvertently placed on the mandrel, or if for any other reason excessive pressure would otherwise be applied to the mandrel, the overload device prevents the application of the excessive pressure so that the cantilevered mandrel is not bent from its normal position.

20 These and other features, objects and advantages of this invention will be apparent from the following detailed discussion when read with reference to the accompanying drawings, in which:

25 FIG. 1 is an end elevation view of a can body forming machine constructed in accordance with this invention with portions cut away to show the mandrel, the forming wings, and portions of the mechanism for actuating the clamping shoe;

30 FIG. 2 is a vertical longitudinal section through the mandrel and clamping device taken generally along lines 2—2 of FIG. 1;

35 FIG. 3 is a vertical cross-section taken generally along the lines 3—3 of FIG. 2 illustrating the structure of the clamping device and the forming wings, and showing the clamping shoe in the clamping position;

40 FIG. 4 is a partial cross-section similar to FIG. 3 illustrating the clamp actuating mechanism in the release position;

45 FIG. 5 is an enlarged perspective view of one of the plate springs for holding the two adjusting wedges in tight abutment; and,

50 FIG. 6 is a somewhat schematic perspective illustration of the mechanism for driving and coordinating actuation of the clamping device and the can forming wings.

Referring to FIGS. 1-3, the can body machine includes a main frame 2 from which a cylindrical can body mandrel or horn 4 is cantilevered. A pair of rails 6 and 8, one of which has a chamfered inner edge 10, are disposed on opposite sides of the mandrel 4 to support a flat can body blank 12 by its edges in position over the mandrel. The can body blank is moved through the can forming station by a feed bar (not shown) to abutment with a positioning lug 14 along each rail 6 and 8. A pair of forming wings 16 supported from the frame are adapted to be pivoted from an open position (shown in phantom in FIG. 1) above the blank 12 to force it off of the inner edges of the rails 6 and 8 and fold the blank about the cylindrical mandrel to form a cylindrically shaped can body. The inner surface 18 of each forming wing 16 is semi-cylindrical to conform to the shape of the mandrel. Each of the forming wings 16 is pivotally mounted on a pin 20 at the lower end of a support bracket 22 which depends from the main frame 2.

Referring to FIGS. 1 and 6, the drive for the wings includes a pair of vertical actuating rods 24 mounted on cranks 26 fixed to parallel driven shafts 28 which rotate to cause the actuating rods 24 to reciprocate up and down.

A roller at the upper end of each actuating rod 24 is mounted in an adjusting slot 32 of a lever 34 which is pivotally mounted on a stub shaft 36 supported on the frame 2. Through the action of the actuating rods, the lever 34 oscillates up and down as the driven shaft 28 rotates. A short connecting rod 37 affixed between the distal end of each lever 34 and a respective one of the forming wings 16, opens and closes the forming wings responsive to rotation of the driven shafts 28 and oscillation of the lever 34. Each of the actuating rods 24 includes a spring barrelled shock absorber 38 for buffering unusual loads and shocks applied to the wings.

The above-described structure, as well as the expanding and seam bumping mechanism, is generally similar to that disclosed in applicant's prior Patent No. 3,100,470, issued Aug. 13, 1963, and reference is made to that patent for additional details of the can forming machine not specifically described herein.

Referring now to FIGS. 2 and 3, the support bracket 22 partially houses a clamping shoe member which includes a clamping shoe 40 and rods 44. The clamping shoe 40 extends out of the lower portion of the bracket and rests on the mandrel 4. The sides of the support bracket 22 fix the clamping shoe 40 against lateral movement. Pins 42 extend from the clamping shoe into the vertical guide rods 44 which are received in vertical sleeves through the support bracket to fix the shoe against longitudinal movement relative to the support bracket. The guide rods 44 and the clamping shoe 40 are free to reciprocate vertically within the support bracket, but the clamping shoe is urged down against the mandrel 4 by light springs 46 housed within the bracket and the ends of the clamping shoe. The trailing edge 48 of the clamping shoe is chamfered so that a can blank conveyed in the direction of the arrow 50 strikes the chamfered shoe edge 48 and raises the shoe sufficiently that the blank can pass into position between the shoe and the cantilevered mandrel.

An adjusting wedge assembly includes a lower wedge 52 which extends longitudinally through the support bracket 2, and is fixed against longitudinal movement relative to the bracket by plungers 54 each of which has a body portion 56 received in an aperture in the support arm and a reduced diameter tip 58 which fits into an aperture 60 in the lower wedge 52. Springs 62 through the plungers 54 urge the wedge assembly upward. The lower wedge 52 has two longitudinally spaced inclined surfaces 64 on its upper face, both inclined from one end 66 of the wedge toward the other 68. An upper adjusting wedge 70 has two inclined surfaces 72 on its lower face which rest on the upper inclined surfaces 64 of the lower wedge. The inclined surfaces of the upper and lower wedges are held in tight engagement by a pair of plate springs 74 (see also FIG. 5) of generally W-shaped configuration which are attached to the respective wedge members by dowel pins 76 extending from the wedges through apertures 78 in the plate springs to form a connected wedge assembly.

The longitudinal position of the upper wedge 70 relative to the lower one 52 is fixed by a pair of bolts 80 which extend through threaded bores in opposite end portions of the lower wedge and abut the ends 82 and 84 of the upper wedge. By adjusting the penetration of the bolts 80, the longitudinal position of the upper wedge relative to the lower can be adjusted. A lock nut 86 on each bolt holds against movement from the adjusted position under operation.

A bearing block 88 fixed to the frame 2 rotatably mounts an elongate shaft 90 directly over the upper wedge 70. A cap 102 bolted on one end of the shaft 90 bears against one end of the block 88 and a collar 103 fixed on the other end of the shaft 90 bears against the other end of the block 88 to hold the shaft longitudinally relative to the frame 2. The shaft 90 has a longitudinal groove 92 formed in its lower side forming an elongate rotary bearing surface of arcuate concave cross-sectional con-

figuration, and the upper wedge 70 has a similar groove 94 formed in its upper surface. An elongate toggle link 96 has a tongue portion 98 and 99 along each of its two edges, the tongues being spaced-apart by a short body portion 100. The upper tongue 98 extends through a slot 105 in the bottom of the bearing block and into the bearing groove 92. The lower tongue 99 extends into the bearing groove 94. The toggle link is held longitudinally by the portions 104 and 107 of the block 88 at each end of the slot 105.

Referring now particularly to FIGS. 1 and 6, the main drive shaft 106 of the machine is rotated by a suitable motor (not shown) to rotate a driving gear 108 in the direction of the arrows. The driving gear 108 rotates a pair of gears 110 fixed on parallel shafts 28 which rotate the cranks 26 and reciprocate the actuating rods 24. Each of the rods 24 oscillates one of the levers 34 about its stub shaft 36 to pivot the forming wings 16 about pins 20 and open and close the wings 16 about the mandrel 4, thereby forming the cylindrical can body. A rotary cam 112 having a raised cam portion 114 on its periphery is also mounted on one of the driven shafts 28. A crank arm 116 fixed on one end of a torsion rod 118 which is rotatably mounted on the machine frame has a roller 120 on its free end which rides on or off the raised portion 114 of the cam to oscillate the torsion rod 118. A second crank arm 122 fixed to the other end of the torsion rod 118 is connected to the lower end of a connecting rod 124 thereby causing the connecting rod 124 to reciprocate as the torsion rod 118 oscillates. The upper end of the connecting rod 124 is connected to one arm 126 of a pivot crank 128 which is pivotally mounted on a crank pin 130 fixed to the frame of the machine. A second arm 132 which extends from the pivot crank in the opposite direction is connected to one end of a connecting link 134 which has its other end pivotally connected to a crank arm 136 on the collar 103 which is keyed on the end of the elongate clamp driving shaft 90.

As is illustrated most clearly in FIGS. 3 and 4, as the elongate clamp driving shaft 90 oscillates through an angle α , preferably about 10° , the toggle link 96 moves from a position in which a plane P through the centers of its arcuate bearing surfaces is aligned with the longitudinal axis 138 of the clamp driving shaft 90 (as shown in FIG. 3) to a position in which the plane P is not aligned with the shaft axis 138 (as shown in FIG. 4). In the aligned position of FIG. 3, the link 96 forces the upper 70 and lower 52 wedges downward against the guide rods 44, thereby applying pressure to the clamping shoe 40 and forcing it down tightly against a can blank 12 to clamp the blank to the mandrel 4. As the clamp driving shaft 90 is oscillated to the position of FIG. 4, the distance from the shaft axis 138 to the lower bearing surface of the toggle link is shortened so that pressure is relieved from the wedges 70 and 52 and the formed can body is released from the clamping shoe 40 and may be conveyed away from the forming station. In the released position, the springs 62 urge the wedge assembly upward away from the rods 44 to maintain good contact between the bearing surfaces of the toggle link 96 and the bearing grooves 92 and 94, and also to take the weight of the wedge assembly off of the shoe. After a new can body blank comes under the clamping shoe, the clamp driving shaft 90 returns to the aligned position to force the wedge assembly against the upper end of the rods 44 and repeat the sequence, the operation of the forming wings 16, the expanding and seam bumping mechanisms (not shown), and the clamping shoe being carefully coordinated through the common drive.

While this invention has been described with reference to a particular embodiment, the scope of the invention should not be limited to that embodiment, but instead should be measured by the following claims.

I claim:

1. In a can forming machine having an elongate man-

mandrel about which a can body is formed and a shoe for alternately clamping and releasing a can blank against the mandrel, means for actuating the clamping shoe comprising:

- a clamping shoe assembly; 5
- means mounting the clamping shoe assembly for reciprocation toward and away from a can forming mandrel to clamp and release a can blank on the mandrel;
- an elongate shaft rotatably mounted alongside the clamping shoe assembly; 10
- opposed concave arcuate bearing surfaces on the shaft and clamping shoe assembly;
- a toggle link connecting the clamping shoe assembly and shaft to reciprocate the clamping shoe assembly responsive to oscillation of the shaft, said toggle link including two spaced-apart bearing surfaces of convex arcuate cross-sectional configuration each received in and conforming to a respective one of the concave bearing surfaces; and, 15
- means for oscillating the elongate shaft to actuate the clamping shoe.

2. In a can forming machine having an elongate mandrel about which a can body is formed and a shoe for alternately clamping and releasing a can blank against the mandrel, means for actuating the clamping shoe in accordance with claim 1 wherein the means for oscillating the elongate shaft includes:

- a power-driven main drive shaft;
- a reciprocable rod eccentrically connected to the elongate shaft and operably connected to the drive shaft for oscillating the elongate shaft responsive to rotation of the main drive shaft; and,
- overload means in said rod for absorbing excessive shock applied to said shoe. 30

3. In a can forming machine having an elongate mandrel about which a can body is formed and a shoe for alternately clamping and releasing a can blank against the mandrel, means for actuating the clamping shoe in accordance with claim 1 wherein:

- the concave bearing surfaces are the walls of elongate parallel grooves in the clamping shoe assembly and elongate shaft; and,
- the toggle link is an elongate member extending along the grooves and having the convex bearing surfaces formed on two of its longitudinal edges. 45

4. In a can forming machine having an elongate mandrel about which a can body is formed and a shoe for alternately clamping and releasing a can blank against the mandrel, means for actuating the clamping shoe in accordance with claim 1, and further comprising spring means maintaining the bearing surfaces of the toggle link in contact with the bearing surfaces of the shaft and clamping shoe assembly. 50

5. In a can forming machine having an elongate mandrel about which a can body is formed and a shoe for alternately clamping and releasing a can blank against the mandrel, means for actuating the clamping shoe in accordance with claim 1, wherein the clamping shoe assembly includes:

- a clamping shoe member for engaging a blank on the mandrel, said clamping shoe member being mounted for reciprocation over the mandrel;

an adjusting wedge assembly mounted over the clamping shoe member for vertical reciprocation relative thereto between a clamping position in which the wedge assembly applies downward pressure to the clamping shoe member, and a release position in which the wedge assembly is spaced from the clamping shoe member, the concave bearing surface of the clamping shoe assembly being on the adjusting wedge assembly; and, 65

spring means for urging the adjusting wedge assembly upward away from the clamping shoe member

and maintaining contact between the respective bearing surfaces of the toggle link, shaft and clamping shoe assembly.

6. In a can forming machine:

- a frame;
- a generally cylindrical can forming mandrel cantilevered from the frame;
- a support member depending from the frame over the mandrel;
- a pair of opposed forming wings pivotally mounted on the support member and adapted to be pivoted between an open position above a can blank and the mandrel and a closed position around the can blank and mandrel;
- an elongate clamping shoe supported on the mandrel and having a clamping surface on its lower face; means on the mounting member fixing the clamping shoe against longitudinal or side-ways movement; spring means connected to said shoe and to said mounting member urging said clamping surface against the mandrel;
- a chamfered edge on the clamping shoe for cooperation with a can body blank to raise the clamping surface from the mandrel;
- a wedge assembly mounted for reciprocation in the support member above the clamping shoe, said wedge assembly including a lower wedge having its upper surface inclined and an upper wedge having its lower surface inclined;
- plate spring means connected to said upper and lower wedges to hold said inclined surfaces in abutment;
- an elongate groove of arcuate cross-sectional configuration formed in the upper surface of the upper wedge;
- means for moving one of said wedge members relative to the other to adjust the distance between the clamping surface and said groove;
- an elongate shaft oscillatably mounted on the can forming machine over the wedge assembly;
- an elongate groove of arcuate cross-sectional configuration formed in the elongate shaft;
- an elongate toggle link including a pair of elongate tongues inserted in said grooves, said tongues being spaced-apart by a body member and each including an elongate bearing surface of convex cross-sectional configuration conforming to the groove in which it is inserted;
- spring means urging the wedge assembly upward against the toggle link; and,
- means for oscillating the elongate shaft to alternately force the clamping shoe against a can body on the mandrel and release the downward pressure from the shoe.

7. In a can forming machine in accordance with claim 6, wherein the means for oscillating the elongate shaft includes:

- a power-driven main drive shaft;
- a reciprocable rod eccentrically connected to the elongate shaft and operably connected to the drive shaft for oscillating the elongate shaft responsive to rotation of the main drive shaft; and,
- overload means in said rod for absorbing excessive shock applied to said shoe. 60
